BOLSTER SPRINGING AND SNUBBING MEANS

William T. Rossell, New York, N. Y., assignor to Transit Research Corporation, New York, N. Y., a corporation of New York

Application March 10, 1950, Serial No. 148,795

12 Claims. (Cl. 105—187)

This invention relates to rail trucks of the type equipped with a bolster mounted on springs for vertical and lateral movements with respect to the main frame of the truck and has for its object to provide an improved springing system for the bolster by which the bolster will be entirely free of snubbing friction in its central position but which will be snubbed in response to lateral swinging movements of the bolster in proportion to the amount or degree of such movements.

Basically, a sprung bolster is supported for relative vertical movements with respect to its truck frame and for lateral movements relative thereto in a plane normal to the frame side rails. Where snubbers are provided they are carried by the side rails or by transoms and contact of the bolster with the snubbers usually depends entirely on acceleration or deceleration of the truck frame with respect to the bolster. The snubbing action may, therefore, not be available at all times when needed, as it is obvious that lateral reactions of the truck frame with respect to the body often occur at times when there is no such relative acceleration. As a solution to the above problem hydraulic shock absorbers, or spring suspensions of a type to throw the bolster against a snubber in response to vertical loading have been proposed. The disadvantage of these solutions is that resistance to any movement of the bolster is then provided so that numerous vibrations are passed from the truck to the car body at all times while the body is moving. Further, the hydraulic shock absorbers offer resistance in proportion to the speed of movement of the bolster whereas it is decidedly preferable for the degree of damping to depend upon the amplitude of the movement thereof.

The object of this invention is to provide a snubbing arrangement such that the bolster is free of all snubbing resistance in its central or near central position, thus eliminating the constant transfer of small vibrations to the body, but which increases its effect with increased swinging of the bolster. By thus causing snubbing according to the position of the bolster the bolster supporting springs may be made softer in a lateral direction.

More particularly it is an object of this invention to provide a springing means for supporting each end of a bolster so that the bolster may swing between guiding frictional surfaces and to so construct and arrange the springing means and the frictional surfaces that the bolster swings freely at or near its center position but which is deflected by the springing means in response to swinging so that its pressure against the frictional surfaces will increase as the swinging movement increases. Another way of explaining the response is to say that the springing means reacts angularly to the force of the bolster swing thus deflecting the ends of the bolster against the friction pads so that one component of the resultant force is longitudinally of the truck frame thus causing snubbing and that the other component is laterally thereof representing the springing. In order for this requirement to be true it is seen that the reaction

2

of the springing means must be in a plane or planes which do not contain the longitudinal axis of the bolster.

In preferred form, the springing means reacts to lateral swinging movements of the bolster in such manner that the ends of the bolster tend to rotate horizontally about the king pin center in the same direction thus biasing the bolster against diagonally opposite friction surfaces (or snubbing pads) but this is not essential since, in one form of the invention, the ends of the bolster tend to rotate horizontally in opposite direction in response to bolster swinging movements thus deflecting the bolster against frictional surfaces on the same side thereof.

Another object of the invention is to teach the adaptation of the invention to a wide variety of operating requirements so that it will be obvious that it may be applied to various services operating at various speeds and under various track conditions so that riding comfort may be varied with the desires and ideas of the operator.

Other objects and advantages will become hereinafter more fully apparent as reference is had to the accompanying drawings wherein my invention is illustrated and in which

Figure 1 is a top plan view of a rail truck equipped with my invention, the left end of the bolster being omitted for purposes of explanation,

Figure 2 is a side elevation of the truck of Figure 1,
Figure 3 is a vertical section taken along the lines 3—3 of Figure 1,

Figure 4 is a top plan view of the upper spring cap of the spring of Figure 3,

Figure 5 is a bottom plan view of the lower spring cap of the spring of Figure 3,

Figure 6 is a top elevation of a modified form of bolster,

Figures 7 and 8 are vertical sections taken along the lines 7—7 and 8—8 respectively of Figure 6 showing the bolster spring assemblies and their supports,

Figures 9, 12, 15 and 20 are top elevations of the same type bolster as shown in Figure 6,

Figures 10 and 11 are vertical sections taken along the lines 10—10 and 11—11 respectively, of Figure 9 showing modifications of the spring assemblies which support the bolster,

Figures 13 and 14 are vertical sections taken along the lines 13—13 and 14—14 of Figure 12 showing other modifications of the spring assemblies,

Figures 16 and 17 are vertical sections taken along the lines 16—16 and 17—17 respectively, of Figure 15,

Figure 18 is a top elevation of a bolster similar to that of Figure 1,

Figure 19 is a vertical section taken along the line 19—19 of Figure 18 showing an adjustment of the spring assemblies to a position different from that shown in Figures 1 and 3,

Figures 21 and 22 are vertical sections of the bolster of Figure 20 showing spring assemblies as in Figure 6 but with the adjustments of the assemblies differently positioned.

More particularly, the numeral 1 indicates the wheels of a rail truck having main side frames 2. The side frames are each connected to axle housings 3 which house the axles (not shown) which are mounted in the wheels 1. Cross members 4 connected to both side frames 2 support the main driving motors 5 which are connected to the axles by propeller shafts 6 through gearing contained in the axle housings 3. The truck herein illustrated is a street car truck but the invention is not limited to self-propelled trucks and may find wide application to trailer trucks of various types.

The bolster 7 has the usual center bearing 8a and is supported at each end by spring assemblies best seen in Figure 3 and as will be hereinafter described. The bolster

is capable of vertical and lateral swinging movements and is guided in its lateral swinging movements by blocks of rubber 8 positioned fore and aft of each end of the bolster and carried by brackets 9. These rubber blocks 8 with the adjacent surfaces of the bolster provide rubber to metal friction when the bolster is in contact with the blocks 8. Even if the blocks 8 were adjusted for continuous contact with the bolster this condition would not hold true after slight wear so that the normal condition is for the blocks to have slight clearance with the ends of the bolster. According to this arrangement the bolster thus swings freely between the blocks but in the event of relative movement of the bolster with respect to the truck frame in the direction of travel of the truck the blocks act as snubbers for bolster swinging movements.

This same or an equivalent arrangement of frictional snubbing surfaces fore and aft of each end of the bolster is contemplated with each of the modifications shown in Figures 6 to 22 inclusive.

The spring assembly of Figure 3 is composed of a nest of springs composed of a large coil spring 10, a smaller coil spring 11 and a rubber spring 12 all of which have a common spring cap 13 over the top thereof and a spring cap 14 for the bottom thereof. The upper cap 12 has a rocker 15 which can rock with respect to the bolster, and the lower cap 14 has a rocker 15 which can rock on the side frame 2. These two rockers are parallel with each other and both are angularly disposed both with respect to the side frames 2 and the direction of swing of the bolster. The rockers at one side of the truck are angularly disposed with respect to each other, as shown in Figure 1.

The operation is as follows: since the rockers are angularly disposed with respect to the side frames they lend stability to the spring nests. During operation of the truck the bolster is free to swing at or near its central position. As the bolster swings to the right (Figure 1) the right springs deflect laterally and the springs tilt in a direction away from the reader thus imparting a counter-clockwise torque to the right end of the bolster. The swinging force of the bolster is thus broken into two components one of which represents the lateral springing while the other component acts to press the upper end of the bolster in contact with the rubber pad 8 on that side of the bolster. The left hand end of the bolster rocks its springs in the direction of the reader and sets up a counterclockwise torque also which forces that end of the bolster in contact with rubber pad 8 on the side of the bolster diagonally opposite to the block 8 under pressure by the right end. The action is thus to bias the bolster in its snubbers in a counter-clockwise direction about the king pin bearing. The foregoing was explanatory of the movement of the bolster to the right (Figure 1). Now suppose that it swings back to its center and continues therewith toward the left. In that case, the spring assembly at the right end will tilt about its rockers toward the reader and the spring assembly at the left end thereof will tilt away from the reader. The biasing effect is then reversed so that the right end will now have snubbing action against the block 8 nearest the reader and the left end will snub against the block 8 away from the reader. The action is thus in a clockwise direction. The pressure of the bolster ends against their snubbers, which may be called the biasing effect, will be proportionate to the swinging movement of the bolster, that is, proportionate to the distance through which the bolster swings and is therefore not related to the speed or acceleration of the swinging movement.

Figure 1 illustrates these rockers as being disposed at an angle of the order of 45° to the center line of the bolster. Figure 3 illustrates handles 17 on the spring caps 13 and 14. By rotation of the caps the angle of the rockers 15 and 16 with respect to the bolster center line may be altered. If, for example, the rockers of the spring assembly at the right end of the bolster are gradually rotated clockwise and those at the left end counter-clockwise

then the component of the swinging force causing snubbing will become gradually reduced in favor of the other or springing component. In other words, the biasing effect will be thus reduced. On the other hand, if the 5 rockers are oppositely rotated the snubbing effect will be increased. Other effects may be obtained by rotating the rockers of the upper caps out of parallel with the rockers of the lower caps as will be hereinafter more fully explained.

10 Figures 6, 7 and 8 illustrate the invention as applied to a bolster 18 having two spaced spring assemblies 19 and 20 supporting each end thereof. In this case each spring 21 and 22 of the spring assemblies 19 and 20 is provided with an upper spring cap 23, the lower ends of each spring 15 resting firmly on a side frame 24. The caps 23 are each provided with rockers 25. The rockers 25 of the spring assemblies at each side of the truck are parallel with each other and form an angle of the order of 45° with the truck side frame and the center line of the bolster 18. 20 The rockers at the right end of the bolster are reversely set to those at the left side. The operation and effect is thus essentially the same as that explained in connection with Figures 1 to 5. Also the spring caps are each individually rotatable with respect to its spring by means 25 of the manual means 26 so that the angularity of the two rockers at each end of the bolster may be varied with respect to the bolster center line and the spring cap of one spring assembly may be rotated with respect to the spring cap of the adjacent assembly, all with the results 30 previously described. In this connection, it should be noted that the angularity of a rocker of the cap of a spring 21 at one end of the bolster should always be disposed at an angle similar to the corresponding spring 21 at the other end of the bolster, and the same requirement applies 35 to the caps of the other two springs 22. It should also be noted in connection with the explanation of Figures 6 to 22 inclusive that, while each spring assembly is illustrated as having a single coil spring that it is contemplated that each could be composed of a spring nest of 40 several springs, an example of which is illustrated in Figure 3.

Figure 9 shows the same bolster 18 illustrated in Figure 6 supported at each end by two spring assemblies 27 and 28. The assemblies 27 are exactly similar to the 45 spring assemblies 19 of Figure 7 and the spring assemblies 28 are the same also but with the spring cap omitted. The two spring assemblies on the same side of the longitudinal center line of the bolster carry the spring caps 29 and the rockers 30, which, in this instance, are illustrated as being normal to the center line of the bolster. The action in this case differs somewhat from that previously described. The spring assemblies 27 offer small resistance to swinging motion of the bolster, as compared with the resistance offered by the assemblies 28. For 50 lateral movements the effect is, thus that these assemblies 27 act like softer springs hence the right end of the bolster will attempt to rotate in a counterclockwise direction and the left end in a clockwise direction in response to a swing of the bolster to the right and this tendency 55 will be reversed after a return swing and on continued swinging to the left.

Figures 12, 13 and 14 show the bolster 18 of Figures 6 and 9 but with spring caps 31 applied both to the top and bottom of both spring assemblies 32 and 33. By 60 making all spring caps manually adjustable by the manual means 34 a very wide variety of operating conditions can be met.

Figures 15, 16 and 17 illustrate the bolster 18 supported by spring assemblies 35 and 36. Assemblies 36 are the 65 same as the assemblies 19 of Figure 6, the springs thereof having similar spring caps 37 with similar rockers 38. The spring assemblies 35 include upper spring caps 39 having buttons 40 instead of the rockers 38. The assemblies 35 thus are freely capable of universal movement with respect to the bolster so that they do not restrain

the bolster in any particular direction. In this case the rockers 38 would not be turned parallel to the truck side frames as there would not be sufficient stability. Obviously, if desired, the spring caps 37 can be omitted from the assemblies 36 where the spring caps with buttons are provided for the assemblies 35.

Figures 18 and 19 show the bolster of Figures 1, 2 and 3 with similar spring assemblies to those shown but with the rockers 44 and 45 of the spring caps 41 and 42 turned at different angles. If both of the rockers were parallel to the side frames 43 there would be insufficient stability but there is stability as soon as either one is rotated out of such parallel relation. With the small relative rotation illustrated, a spring action results that is quite soft laterally and the snubbing effect is pronounced but not severe. If the rockers 44 are further rotated the snubbing action will be increased. However, suppose that the angularity of the rockers 44 is kept as illustrated and an opposite angularity is given to the rockers 45. The snubbing action will be wholly lost since the center line of the bolster will then bisect the angle formed by the rockers.

The foregoing explanations have all been based on the theory that it is best to obtain the biasing or snubbing effect by rotating the bolster about the center of its center bearing. However, it is not essential that this be done since any relative fore and aft displacement of the bolster with respect to the snubbing surfaces can be made to produce snubbing. In Figures 20, 21 and 22 the bolster 18 is supported by the spring assemblies 46 and 47 exactly similar to the spring assemblies 19 and 20 of Figure 6. These assemblies are provided with rockers 49 and 50. The rockers are all set at an angle with respect to the center line of the bolster and at an angle with respect to the truck side frames. The difference between the setting of these rockers and those of Figure 6 is that in this case all four rockers are parallel with each other. Now, as the bolster swings to the right it will be bodily displaced toward the friction blocks on the same side, that is, toward the reader. After it makes its return it will swing bodily into pressure contact with the blocks on its other side, both away from the reader. Any of the other forms illustrated can be made to act similarly. While the action will be effective to snub the bolster, relative bodily movement of the bolster entails movement of the car body supported by the bolster with respect to the truck frame. Much more inertia is involved and the action will not be as smooth as with the other forms which contemplate the angular biasing effect obtained by rotation of the bolster into pressure contact with diagonally opposite friction pads.

It should now be clear that numerous combinations can be selected from the several illustrations herein described and that greatly improved control of a bolster can be had to adapt it to a wide variety of operating conditions. The two springs illustrated at each end of the bolster of certain figures could be made a larger or smaller number and various changes and modifications can be made without departing from the spirit of my invention. I therefore desire to be extended protection as defined by the appended claims.

What I claim is:

1. In a rail truck, a truck frame including side rails, a bolster, spring assemblies supporting each end of said bolster from said frame, frictional surfaces carried by said frame and located fore and aft of each end of said bolster limiting the longitudinal movement thereof with respect to said frame, said bolster when in stable equilibrium being out of pressure contact with said surfaces, said bolster when swinging causing said springs to deflect, and means incorporated in said spring assemblies angularly deflecting the lateral force imposed thereon by said bolster whereby each end of said bolster is impelled into pressure contact with one of its adjacent friction surfaces, said means including at least one rocking support for

each of said assemblies, said rocking support being angularly disposed with respect to the direction of travel of the truck.

5 2. In a rail truck, a truck frame having side rails, a bolster, spring assemblies supporting each end of said bolster from said side rails, frictional surfaces fore and aft of each end of said bolster limiting the longitudinal movement of said bolster with respect to said frame, said bolster when in substantially center position being free of pressure contact with any of said friction surfaces, said bolster when swinging laterally imposing a force on said spring assemblies, said spring assemblies including springs each having a spring cap on at least one end thereof, said spring caps each having a rocker on its face remote from its associated spring angularly disposed with respect to the side rails of said truck frame whereby the lateral force exerted by said bolster on said springs is angularly deflected by said rockers during transmission to said springs, said springs employing the lateral component of said force for springing movements of said bolster and employing the longitudinal component thereof to force each end of said bolster into pressure contact with an adjacent friction surface.

10 3. In a rail truck, a truck frame having side rails and a bolster, spring assemblies supporting each end of said bolster from said side rails, friction surfaces fore and aft of each end of said bolster limiting longitudinal movement thereof with respect to said truck frame, said bolster when in centered position being normally out of pressure contact with said friction surfaces and having its median plane normal to said side rails, said bolster when swinging imposing a force on said spring assemblies, said spring assemblies being constructed and arranged to accept said force through spring caps each having a rocker on the surface thereof exteriorly of the springs of said spring assemblies, said rockers being angularly disposed with respect to said side rails whereby the reaction of said springs tends to rotate each end of said bolster with a force dependent upon the amount of the angularity of said rockers and the extent of the swinging movement of said bolster.

15 4. In a rail truck, a truck frame having side rails, a bolster, spring assemblies supporting each end of said bolster from said side rails, frictional surfaces fore and aft of each end of said bolster limiting the longitudinal movement of said bolster with respect to said frame, said bolster when in substantially center position being free of pressure contact with any of said friction surfaces, said bolster when swinging laterally imposing a force on said spring assemblies, said spring assemblies each including at least one spring having a spring cap and a rocker on which said spring and cap may rock with respect to said bolster or a side frame, said rockers each being angularly disposed with respect to the side rails of said frame whereby each end of said bolster is deflected against two of said friction surfaces with a force dependent upon the angularity of said rockers with respect to said side frames and the extent of the swinging movement of said bolster.

20 5. In a rail truck, a truck frame having side rails, a bolster, spring assemblies supporting each end of said bolster from said side rails, frictional surfaces fore and aft of each end of said bolster limiting the longitudinal movement of said bolster with respect to said frame, said bolster when in substantially center position being free of pressure contact with any of said friction surfaces, said bolster when swinging laterally imposing a force on said spring assemblies; said spring assemblies each including at least one spring having a spring cap at least one end thereof, said spring caps each having a rocker thereon, the rocker at one end of said bolster being angularly disposed with respect to the rocker at the other end of said bolster whereby lateral swinging movement of said bolster causes said bolster to bias against two diagonally disposed friction surfaces and return swinging movement

of said bolster causes said bolster to bias against the other two diagonally disposed friction surfaces.

6. In a rail truck, a truck frame having side rails, a bolster, spring assemblies supporting each end of said bolster from said side rails, frictional surfaces fore and aft of each end of said bolster limiting the longitudinal movement of said bolster with respect to said frame, said bolster when in substantially center position being free of pressure contact with any of said friction surfaces, said bolster when swinging laterally imposing a force on said spring assemblies, said spring assemblies each including at least one spring having a spring cap at its upper end equipped with an integral rocker in rocking engagement with respect to said bolster, said spring caps with their rockers being rotatably adjustable with respect to their respective springs and said bolster whereby the angle of reaction of said springs to the force imposed thereon by said bolster during swinging movements may be adjusted thereby adjusting the biasing imparted to said bolster by said springs.

7. In a rail truck, a truck frame having side rails, a bolster, spring assemblies supporting each end of said bolster from said side rails, frictional surfaces fore and aft of each end of said bolster limiting the longitudinal movement of said bolster with respect to said frame, said bolster when in substantially center position being free of pressure contact with any of said friction surfaces, said bolster when swinging laterally imposing a force on said frictional surfaces, said spring assemblies each including at least one spring having a spring cap at its upper and lower ends, each of said spring caps being equipped with a rocker for contact with said bolster and a side rail respectively, at least one rocker of each of said assemblies being angularly disposed with respect to said side rails.

8. In a rail truck, a truck frame having side rails, a bolster, spring assemblies supporting each end of said bolster from said side rails, frictional surfaces fore and aft of each end of said bolster limiting the longitudinal movement of said bolster with respect to said frame, said bolster when in substantially center position being free of pressure contact with any of said friction surfaces, said bolster when swinging laterally imposing a force on said spring assemblies, said spring assemblies each including at least one spring having a spring cap at its upper and lower ends, each of said spring caps being equipped with a rocker for contact with said bolster and a side rail respectively, the rockers of the same spring assembly being adjustable for positioning in relative parallel or relative non-parallel positions.

9. In a rail truck, a truck frame having side rails, a bolster, spring assemblies supporting each end of said bolster from said side rails, frictional surfaces fore and aft of each end of said bolster limiting the longitudinal movement of said bolster with respect to said frame, said bolster when in substantially center position being free of pressure contact with any of said friction surfaces, said bolster when swinging laterally imposing a force on said spring assemblies, said spring assemblies each comprising two sets of springs at each end of said bolster arranged in side-by-side relation, one spring of each of said sets being mounted to rock to a greater extent than the adjacent spring in the same set under swinging movements of said bolster whereby the lateral force exerted by said bolster is deflected out of a path normal to said side rails.

10. In a rail truck, a truck frame having side rails, a bolster, spring assemblies supporting each end of said

bolster from said side rails, frictional surfaces fore and aft of each end of said bolster limiting the longitudinal movement of said bolster with respect to said frame, said bolster when in substantially center position being free of pressure contact with any of said friction surfaces, said bolster when swinging laterally imposing a force on said spring assemblies, said spring assemblies each comprising two sets of springs arranged in side-by-side relation, one of said spring sets of each of said assemblies comprising a spring having a spring cap, said caps each having a substantially hemispherical ball integral therewith constituting a rocker for said cap whereby said spring assemblies deflect the bolster out of a transverse path normal to said side rails and urge said bolster against one friction pad adjacent each end thereof, the other of said spring sets also comprising a spring having a spring cap top and bottom thereon, the last named caps each having a rocker on the surface thereof opposite said springs, said rockers being positioned parallel to the direction of swinging motion of said bolster.

11. Bolster support means for use with a rail car truck frame comprising, vertically extending spaced apart spring members supported on said truck frame, a bolster, the ends of said bolster overlying said spaced apart spring members, means between said spring members and said bolster for translating endwise movement of the latter into sidewise movement thereof, and said means being disposed diagonally at a predetermined angle from a vertical lengthwise plane passing through the rail car truck.

12. Bolster support means for use with a rail car truck frame comprising, vertically extending spaced apart spring members, horizontal plate members carried at the upper ends of each of said spring members, a bolster, the ends of said bolster overlying said plate members, blade members between said plate members and said bolster for translating endwise movement of the latter into sidewise movement thereof, said blade members being disposed diagonally at a predetermined angle from a vertical lengthwise plane passing through the rail car truck, and resilient block members disposed on each side of said bolster adjacent each end thereof, said blade members causing said bolster to be urged into frictional engagement with the pair of said block members on the one side of said bolster as the latter moves endwise, and said block members offering an increased rate of resistance to endwise movement of said bolster as the force with which said bolster is urged into engagement with said block members increases.
